H. S. WOLFF

STOCKING

Filed Feb. 18, 1928

Harry S. Wolff ^{Inventor}
By his Attorney
Frederick W. Bunker

UNITED STATES PATENT OFFICE.

HARRY S. WOLFF, OF NEW ROCHELLE, NEW YORK.

STOCKING.

Application filed February 18, 1928. Serial No. 255,243.

This invention relates to hosiery and my improvement is directed to means provided at the back of a stocking or other hose for establishing at each side of the vertical centre thereof, suitably spaced therefrom, visual linear indications that symmetrically follow the leg contour for the purpose of creating an optical illusion whereby the wearer's leg appears slenderized.

Particularly with the present short skirt fashion, causing a considerable length of leg to be exposed, women whose legs are stouter than the average experience the need for some means whereby the stout and sometimes ungainly appearing effect may be modified, so that the outlines of their legs may approximate in appearance curvatures that conform more nearly to a generally accepted standard of leg beauty.

So far as I am aware no attempt has heretofore been made of according such treatment to a stocking as will have the effect of slenderizing the appearance of the leg upon which it is worn, and in consequence, I believe my invention to constitute a new and useful branch in the art of stocking manufacture.

The linear indications at the back of the stocking may be produced by providing a double thickness of material of the same character and shade or tint as that of the stocking itself, or if desired to accentuate the indications they may comprise strips of different character or different shade or tint, or even of different color. Or these indications may be produced by any other available known means.

Other features and advantages of my invention will hereinafter appear.

In the drawing:

Figure 1 is a perspective elevation of a stocking, shown upon a wearer's leg, and embodying my improvement, and Fig. 2 is a rear elevation thereof.

In said views let 1 indicate a stocking, fitted upon a leg 2.

The stocking foot is shown as provided with the usual extra thickness of material, indicated at 3, for reinforcement purposes, to increase its durability and wearing qualities.

In the example of my invention herein illustrated this extra thickness of material

is extended upwardly, from the heel portion thereof, in two separate widths, comprising linear indications 4, 5 that are in spaced relation with respect to each other, and that are each equi-distant from the true rear vertical centre of the stocking, said vertical centre being indicated in the example by a seam line 6.

Also it will be noted that the indications 4, 5 are in approximate parallelism, both with respect to each other and the seam line indication.

It will be appreciated that the linear indications are to be spaced apart a greater or less extent to suit the girth or bulk of the leg upon which the stocking is worn, the spacing being greater for a leg of considerable bulk and less when the slenderizing effect to be achieved is with respect to a more moderate sized leg. In consequence the extent of the spacing between the linear indications will vary with the girth amplitude of the stocking.

It will be noted that the reinforcement portions that extend upwardly from the heel do not overlay or connect with the seam, so that the bulk of the seam is not increased thereby, said seam instead lying exposed between the opposed parallel edges of said reinforcement portions. Also it will be observed that the opposed edges of said reinforcement portions have straight lines and are in equi-spaced relation with the seam and each other throughout the extent of said portions, from the heel reinforcement upwardly.

Variations within the spirit and scope of my invention are equally comprehended by the foregoing disclosure.

I claim:

1. The combination in a stocking having a rearwardly central vertical seam and provided with reinforcement at its heel, of portions of reinforcement of similar shape and size extended substantially the full length of the seam at opposite sides thereof from heel to top, said portions of reinforcement being substantially parallel to the seam and having straight edges in close proximity thereto.

2. The combination in a stocking having a rearwardly central vertical seam and provided with reinforcement at its heel only,

of portions of reinforcement of similar shape and size extended vertically, converging upwardly and symmetrically disposed at opposite sides of said seam, said portions 5 having straight opposed edges that are in equi-spaced relation throughout from each other and said seam from the heel upwardly in close proximity to said seam, to avoid clocks, thereby exposing the seam to avoid increasing its bulk and producing a slenderizing effect with respect to a leg encased by the stocking.

New York, February 15th, 1928.

HARRY S. WOLFF.
